LUGGAGE LOCK OR SIMILAR ARTICLE

Charles S. Gehrie, Montclair, N.J., assignor to Presto Lock Co., a limited partnership

Filed Apr. 5, 1962, Ser. No. 69,593

Term of patent 14 years

(Cl. D50—7)

FIG. 1

FIG. 2

FIG. 4

FIG. 1 is a top plan view of a luggage lock or similar article embodying my new design;

FIG. 2 is a side elevational view looking toward the left side of FIG. 1;

FIG. 3 is a side elevational view looking toward the right side of FIG. 1; and

FIG. 4 is a front elevational view.

The dominant feature of my design resides in the full line showing.

I claim:

The ornamental design for a luggage lock or similar article, as shown and described.
